UNITED STATES PATENT OFFICE

2,243,823

TUBULAR ELECTRIC RESISTANCE
HEATING ELEMENT

Christian Bergh Backer, Bromley, England

Application January 30, 1939, Serial No. 253,526
In Great Britain February 1, 1938

1 Claim. (Cl. 201—64)

This invention relates to tubular electric resistance heating elements of the kind in which a coiled resistance wire, which is surrounded by insulating material, is enclosed in a metallic tube or sheath.

For many purposes tubular electric heating elements must withstand temperatures which may amount to from 600—850° C. The tube or sheath in which the heating element and the insulating material are enclosed must then be capable of resisting temperatures up to 900° C. and must therefore be made of a heat resisting material, for example a nickel-chromium alloy or stainless iron or steel of suitable quality. To draw tubing from such heat resisting alloys is extremely difficult and the cost of a seamless drawn tube, or even of a welded tube which must be drawn after welding, may amount per pound weight to 8—10 times the cost of the alloy in sheet form. The tubing therefore is too expensive in most cases to be used in the manufacture of heating elements. On the other hand, the cost of such heat resisting alloys in the form of sheet is not prohibitive.

I have now devised a method whereby tubing can be made from such heat resistant alloys at a cost which is sufficiently low to allow the tubing, which is very suitable for use in the manufacture of tubular electric resistance heating elements, to be used for this purpose. The tubing is made from a sheet or strip of heat resisting alloy by bending the sheet or strip into the form of a tube which may be of circular or other cross section, in such a way that the longitudinal edges of the sheet or strip lie in contact with one another and form a protruding rib on the outside of the tube. The protruding edges which form the rib are then welded together, preferably by an electric seam welder, whereby the tube becomes watertight.

The invention therefore consists in an electric resistance heating element which comprises a coiled resistance wire which is surrounded by or embedded in insulating material and enclosed in a tube made in the manner described from a sheet or strip of heat resisting alloy, for example a nickel-chromium alloy or a suitable stainless iron or steel alloy.

For certain purposes the protruding rib may not be desirable but in the majority of cases the presence of the rib is not disadvantageous and it may even be an advantage. In any case the rib helps to stiffen the tube and prevent it from bending, while, for many types of heating elements such as tubular boiling plates, grill elements, room heater elements and so forth the rib

affords a convenient means of fastening the element, for example by spot welding, or otherwise, to a supporting frame or structure.

The presence of the rib does indeed increase the difficulty of bending the tube, which will usually be necessary, nevertheless it has been found that, if proper bending tools are employed, the tubing may be bent to any required shape and even very sharp bends may be made. The rib also may be positioned in any desired plane with respect to the plane of the bend, that is to say, the tube may be bent with the rib either on the outside or on the inside of the bend or the rib may be perpendicular to the plane of the bend. 15 The latter type of bend is the easiest to make because the rib is only stretched to a very small extent. When the rib is on the outside of the bend it has to be stretched considerably, especially if the bend is sharp, while when the rib is on the 20 inside it has to be compressed. It has been found that the tubing may be bent to a radius which is slightly more than half the outside diameter of the tubing which is quite sufficient for the manufacture of resistance heating elements of the usual designs.

In order that the invention may be readily understood and carried into effect it will now be described by way of example with reference to the accompanying drawing, in which

30 Figure 1 is an end view showing how the tubing is formed by bending a strip or sheet of heat resisting metal.

Figures 2, 3 and 4 are views showing a bent tube with the protruding rib disposed in different planes relatively to the plane of the bend, and

35 Figures 5, 6, 7 and 8 are cross sectional views of four different forms of tubular electric resistance heating elements constructed in accordance with the invention.

40 Referring to Figure 1 of the drawing, in order to form the tube the longitudinal edges 2 and 3 of a strip of heat resisting metal or alloy are first bent at an angle of approximately 90° to the plane of the strip. The strip is then bent into tubular form so that the longitudinal edges 2 and 3 lie in contact with one another along the line indicated by the numeral 4, after which they are welded together. The tube which has been manufactured in the manner described with reference to Figure 1, can be bent with the plane of the rib disposed in various positions relatively to that of the bend, as illustrated in Figures 2, 3 and 4. The bending should of course be undertaken after

50 the resistance wire and insulating material have 55 been inserted in the tube.

Figures 5, 6, 7 and 8 illustrate different forms of heating elements in accordance with the invention. In these figures, the numeral 5 designates the coiled resistance wire, 6 the insulating material and 7 the tube which is manufactured in the manner described with reference to Figure 1. In the manufacture of the electric heating elements shown in these figures the heating coil and the insulation are first enclosed in a circular tube of the kind shown in Figure 1, after which the tube is deformed in a suitable press to the shape shown in any of the Figures 5, 6, 7 and 8. During the shaping process, the insulating material in the interior of the tube is simultaneously compacted. The rib 8 may be used for fastening the element to any support, for example by spot welding and in addition it assists in stiffening the tube.

For producing the insulation between the re-

sistance coil and the tubular casing and compacting it the methods described in the specification of my prior British Patents Nos. 462,263 and 462,280 may advantageously be employed.

5 I claim:

The method of making an electric heating element which consists in bending two opposite edges of a sheet of metal to form a flange portion on each edge, bending the portion of the sheet between said flanges into tubular form to provide an outwardly projecting rib by contacting said flanges throughout their length, securing the flanges together to produce stiffness of the finished tube, disposing a heating conductor within the tubular portion, packing insulating material around the conductor and bending the tubular portion to form a heating element.
